UNITED STATES PATENT OFFICE

JOSEPH B. JACKSON, OF MILFORD, MASSACHUSETTS, ASSIGNOR TO DRAPER CORPORATION, OF HOPEDALE, MASSACHUSETTS, A CORPORATION OF MAINE

ELECTRIC FEELER MECHANISM FOR LOOMS

Application filed September 26, 1930. Serial No. 484,506.

This invention relates to feeler mechanism for looms and is more particularly directed to feeler mechanisms of the electric type wherein on the completion or interruption of an electric circuit means are set in operation to either stop the loom or cause filling replenishment.

Feeler mechanisms of the electric type have usually consisted of two feeler members mounted in a feeler stand and normally engaged with the terminals of an electric circuit, to complete which on substantial exhaustion of filling in the shuttle a circuit closing member or metal sleeve has been employed on the filling carrier or bobbin for engagement with the ends of the feeler members. The occasional formation of a spark between the ends of the feeler members and the circuit closing sleeve on the bobbin or filling carrier where lint is liable to accumulate has materially affected the adoption of electric feeler mechanisms.

One of the objects of the present invention is to provide a feeler mechanism of the electric type which shall be simple in construction, effective in operation and wherein should a spark occur, it will be so confined remote from any lint or accumulation of fibre that the objections heretofore present will be obviated.

In accordance with the present invention, two single feeler members are mounted upon a feeler stand for movement towards and from the front of the loom, and one of the feeler members is in constant electric connection with one terminal of an electric circuit, while the other feeler member is normally insulated from the second terminal and is brought into contact therewith only after the rear end portions of the feeler members have been electrically closed by contact with a closing member or sleeve mounted upon the filling carrier or bobbin, the effect being that should a spark occur on the make or break of the electric circuit, it will be so confined as to offer no objections.

Another feature of the invention consists in mounting the two feeler members for sliding engagement with the terminals of the

electric circuit, thereby tending for the production of more certain results.

The invention and novel features thereof will best be made clear from the following description and the accompanying drawings of one good form thereof.

In the drawings:

Fig. 1 is a sectional plan view of certain portions of a loom with the present invention applied thereto, some of the parts being broken away; and

Fig. 2 is a front elevation showing the electric feeler mechanism assembled on the loom.

Electric feeler mechanisms may be utilized to change the loom operation either by initiating replenishment or effecting loom stoppage, but since the train of mechanism to effect either of these purposes is now well-known, detailed illustration and description will be unnecessary.

The loom frame 1 may be of any usual construction for the support of the electric feeler mechanism of the present invention, and, as shown, the loom frame 1 has a lateral projection 2 on which is mounted a bracket 3 appropriately secured to the loom frame by a bolt 4 passing through a slot or opening 5 in the lateral projection, the construction being such that the bracket 3 affords an adjustable support for the feeler mechanism.

Surmounting the bracket 3 is the feeler stand 6 which is shown as formed of insulating material, and preferably composed of an upper part 7 and a lower part 8 appropriately secured together.

The two feeler members 9 and 10 are mounted upon the feeler stand 6 for movement towards and from the front of the loom, and each consists of a single stem extending through an opening 11 in the feeler stand and each provided with a head or shouldered portion 12 against which rests the rear end portion of a spring 13, the front end portion of which bears upon a bushing 14 of insulating material, and provided with an opening through which the front portion of the feelers extend with permissive movement towards and from the front of the loom.

In accordance with the present invention, one of the feeler members, 9 in the present instance, is in constant electrical connection with one terminal of an electric circuit, while the other feeler member is insulated from the other terminal of the electric circuit, the result being that when the two feeler members have engaged the circuit closing member on the filling carrier of bobbin in the shuttle upon substantial exhaustion of filling, only one electric contact is necessary to bring about a change in the loom operation.

As shown in the present instance of the invention, the feeler member 9 is relatively longer than the feeler member 10, and the feeler member 9 has its front portion normally in electrical contact with a metal bushing 15 which has a circular recess 16 engaged by a pin or bolt 17 which passes through the insulating stand 6 and engages the recess 16 of the bushing.

The bolt 17 which is described as constantly engaged with the metal bushing 15 constitutes a binding post for one end 18 of an electric circuit 19, and, as shown, Fig. 2, the connection between the end 18 of the electric circuit and the bolt 17 may be appropriately effected by a nut or other binding element secured to the lower end of the bolt 17 by a threaded connection or otherwise.

The second feeler member 10, which is shown as shorter than the feeler member 9, is normally insulated from the other terminal of the electric circuit and, as shown, this is effected by the bushing 14, as described, through which the front end of the feeler member 10 has sliding movement. Frontward of the insulating bushing 14 is a metal bushing 21 which, like the metal bushing 15, is provided with a circular recess 22 which is engaged by a binding post or bolt 23 passed through the insulating casing 6 and engaging the recess 22.

The other terminal 24 of the electric circuit may be secured to the binding post or bolt 23 in an appropriate manner, as indicated in Fig. 2, as by the nut 25 threaded on the bolt 23.

From the construction thus far described it will be noted that the feeler mechanism constituting the present invention includes two feeler members, one of which is in constant electrical communication with one terminal of the electric circuit and the other of which is normally insulated from the other terminal, and both feeler members are mounted in the insulating casing or stand 6 for movement towards and from the front of the loom.

The lay 26 carries the usual shuttle box 27, the front wall 28 of which is provided with an opening 29 which registers with a corresponding opening 30 in the front wall 31 of the shuttle to thereby afford passage

for the two feeler members 9 and 10 into the shuttle on a detecting beat to feel for the filling.

The shuttle 30 is provided with the usual bobbin holding jaws 32 which are detachably engaged by the head 33 of the filling carrier or bobbin 34 on which the filling is wound, and mounted on the filling carrier or bobbin 34 is a circuit closing member 35 which may be conveniently constituted as a metal sleeve to effect electrical connection between the ends of the two feeler members 9 and 10 when the filling is substantially exhausted on a detecting beat, the construction being such that on substantial exhaustion of filling the end portions of the two feeler members 9 and 10 will be engaged by the circuit closing member 35 on the bobbin or filling carrier on a detecting beat and electrically connect the two feeler members, and as the lay beats up, the two feeler members will be moved frontwardly thereby causing the second feeler member 10 to be projected into the metal bushing 21 and form an electric connection between it and the second terminal to thereby complete the circuit. Thus it will be noted that only one electric contact is necessary, that between the feeler member 10 and the bushing 21, in order to complete the circuit and effect a change in loom operation, and in case of the occurrence of a spark during the make or break of the feeler member 10 with the second terminal, such spark will be confined within the insulated casing or feeler stand 6 at a point remote from any lint or other inflammable matter.

As will be apparent from the foregoing description, both feeler members 9 and 10 have sliding engagement with the bushings 15 and 21, thereby maintaining clean surfaces for electric connection between the feeler members and their respective terminals of the circuit.

The completion of the circuit, as hereinbefore described, may be utilized through any train of mechanism to change the loom operation, and as typical of such train of mechanism the present invention shows a magnetic device which may include a solenoid 36 mounted in a casing 37 appropriately secured at 38 to the loom frame.

The core or armature 39 is mounted for sliding movement within the solenoid and has a projecting arm 40 connected to a transmitter 41 whereby movement of the core or armature 39 under the influence of the solenoid when the circuit is completed will cause a change in the loom operation.

The wire 42 which extends from the binding post or bolt 23 is connected to the solenoid, as indicated at 43, and the wire 44 extending from the source of electric energy at 45 is likewise connected to the other end of the solenoid, as at 46, the construction being such that when the circuit is completed, as

hereinbefore described, the solenoid will be energized and the core 39 thereof moved longitudinally to effect either replenishment or loom stoppage.

5 The projecting arm 40 of the core 39 is normally held in its initial position by a light spring 47 and limited under spring stress by a stop 48, with permissive movement of the core 39 under the influence of the energized solenoid. The magnetic device, as herein described, is merely typical of a train of mechanism which may be actuated on completion of the electric circuit through the feeler mechanism to effect either loom stoppage or replenishment of filling.

What is claimed is:

1. In an electric feeler mechanism for looms, the combination of a feeler stand, two feeler members independently mounted on the feeler stand for movement towards and from the front of the loom, one of said feeler members being continuously in sliding electric connection with one terminal of an electric circuit, the second of said feeler members being normally out of electric connection with the other terminal of the electric circuit, a circuit closing member within the shuttle to engage both feeler members when the filling is substantially exhausted and effect movement of the second feeler member into sliding electric connection with the other terminal to complete the circuit as the lay moves frontwardly, and means for changing the loom operation when the electric circuit is completed.

2. In an electric feeler mechanism for looms, the combination of two feeler members mounted for independent movement towards and from the front of the loom, a shuttle having a filling carrier provided with a circuit closing member for contact with both feeler members when the filling is exhausted on a detecting beat, one of said feeler members being normally in sliding electric connection with an electric terminal, the other of said members being normally insulated from the other terminal and caused to slide thereon and complete the circuit after the two feeler members have been engaged by the circuit closing member on the filling carrier, and means for changing the loom operation on completion of the circuit.

3. In an electric feeler mechanism for looms, the combination of two feeler members, one of which is normally in sliding connection with one terminal of an electric circuit and the second of which is normally insulated from the other terminal, a circuit closing member mounted on the filling carrier in the shuttle to close the electrical connection between the two feeler members on substantial exhaustion of filling on a detecting beat and cause the second feeler member to slide on the said other terminal as the second feeler member moves frontwardly sub-

sequent to its engagement with the circuit closing member on the filling carrier, and means rendered effective to effect replenishment of filling when the circuit is completed.

4. In a feeler mechanism for looms, the combination of a feeler stand formed of insulating material, a feeler member constituted as a metallic stem mounted on the stand and in continuous sliding electrical connection with an electric circuit, a second feeler member mounted on the feeler stand and insulated from the electric circuit, a circuit closing member on the filling carrier for engagement with both feeler members when the filling is substantially exhausted on a detecting beat to first close the circuit between said feeler members and then move the second feeler member into sliding connection with the circuit to close the circuit within the feeler stand that any spark may be confined within the stand, and means for changing the loom operation when the circuit is completed.

5. In an electric feeler mechanism for looms, the combination of a feeler stand formed of insulating material, a shuttle having a filling carrier provided with a circuit closing member, two feeler members the rear ends of which engage the circuit closing member when filling is substantially exhausted on a detecting beat, an electric circuit having one of its terminals in continuous sliding engagement with one of the feeler members and its other terminal normally insulated from the second feeler member until the second feeler member is moved frontwardly so that on substantial exhaustion of filling on a detecting beat the circuit will be closed first through the two feeler members and then through the second feeler member by sliding engagement with said second terminal, and means for replenishing the filling on completion of the electric circuit.

6. In an electric feeler mechanism for looms, the combination of a feeler stand, a shuttle having a filling carrier provided with a circuit closing member, an electric circuit, a feeler member having a constant sliding engagement with one terminal of the circuit, a second feeler member normally insulated from the second terminal of the circuit and moved into sliding engagement with said second terminal on the beat up, that upon substantial exhaustion of filling on a detecting beat the rear ends of the feeler members will first engage the circuit closing member on the filling carrier and thereafter the second feeler member will be moved frontwardly to close the circuit through sliding engagement with the second terminal of the circuit.

7. In an electric feeler mechanism for looms, the combination of a feeler stand, an electric circuit, a long feeler member having a constant sliding engagement with one terminal of the circuit, a shorter feeler member normally insulated from the second termi-

nal, a shuttle having a filling carrier provided with a circuit closing member for closing the circuit through the two feeler members on substantial exhaustion of filling and thereafter causing the short feeler member to close the circuit through sliding engagement with the second terminal of the circuit.

8. An electric feeler for looms, comprising a feeler stand formed of insulating material, two feeler members mounted on the feeler stand for sliding movement towards and from the front of the loom, a metallic member constituting one terminal of an electric circuit in constant sliding engagement with one of the feeler members, a second metallic member constituting a second terminal of the circuit and normally insulated from the other feeler member that the latter may have sliding engagement with the second metallic member upon frontward movement of said feeler members.

9. An electric feeler for looms, comprising a feeler stand formed of insulating material, two feeler members of unequal lengths, each formed of a single metallic stem extending from front to rear of the feeler stand, an electric terminal with which the longer of the feeler members is in constant sliding engagement, an electric terminal with which the shorter of the feeler members is normally out of sliding engagement, a metallic member in the shuttle for moving both feeler members frontwardly when the filling is substantially exhausted on a detecting beat to move the shorter feeler member into sliding engagement with its terminal and complete the circuit, and means actuated on completion of the circuit to effect a change in the loom operation.

10. An electric feeler for looms, comprising a feeler stand formed of insulating material, two feeler members of unequal lengths each formed of a single metallic stem extending from front to rear of the feeler stand, a metallic sleeve constituting an electric terminal at the front portion of the feeler stand in which the front end of the longer feeler member has constant sliding engagement, a second metallic sleeve constituting another electric terminal in which the shorter feeler member has sliding engagement only when it is moved frontwardly from its normal rearward position, a metallic member in the shuttle for moving the feeler members frontwardly when filling is substantially exhausted on a detecting beat to complete the circuit, and means actuated on completion of the circuit to change the loom operation.

In testimony whereof, I have signed my name to this specification.

JOSEPH B. JACKSON.
